UNITED STATES PATENT OFFICE.

ALBERT M. BULLARD, OF NEW YORK, N. Y., ASSIGNOR TO WESTERN ELECTRIC COMPANY, OF CHICAGO, ILLINOIS, A CORPORATION OF ILLINOIS.

AUTOMATIC TELEPHONE-EXCHANGE SYSTEM.

No. 826,310.

Specification of Letters Patent.

Patented July 17, 1906.

Application filed October 16, 1905. Serial No. 283,022.

To all whom it may concern:

Be it known that I, ALBERT M. BULLARD, a citizen of the United States, residing at New York, in the county of New York and State of New York, have invented a certain new and useful Improvement in Automatic Telephone-Exchange Systems, of which the following is a full, clear, concise, and exact description.

- 10 My invention relates to an automatic telephone-exchange system; and its object is to provide an improved organization of circuits and apparatus by which the selective switching of any two subscribers' instruments into connection with each other may be accomplished rapidly and with certainty, while meeting the various requirements of signaling, prevention of interference with busy lines, including both testing and "lock-out" 15 features, good telephone transmission, economy of current consumption, and simplicity and cheapness of the apparatus, which are all essential to a thoroughly practicable system.
- 20 The invention has particular reference to such exchanges as are limited to a comparatively small number of subscribers' circuits—say a hundred—some or all of which may be party-lines having several subscribers' instruments connected thereto, although certain features of the invention may be employed with advantage in larger exchanges.

25 The accompanying drawings illustrate an automatic telephone-exchange system which is typical of my invention, and I will describe that system in detail, reserving for the concluding claims a more general statement as to the features, improvements, or combinations believed to be novel.

30 Figure 1 is a circuit diagram of two telephone-lines extending from their respective subscribers' stations to a central office, where each line is equipped with apparatus for performing the various switching operations required in making connection with any other line of the exchange, it being understood that each line of the exchange has an equipment similar to that of the lines shown in Fig. 1. Fig. 2 is a plan view of the selector-switch 35 which is provided for each line at the central office. For a hundred-line exchange one hundred of these selectors would be re-

quired. Fig. 3 is a side elevation of the selector shown in Fig. 2, the supporting-frame thereof being in cross-section. Fig. 4 is a detail plan view similar to Fig. 2, but showing the selector-arm in an advanced position. Fig. 5 shows the controlling mechanism at the subscriber's station by which the operation of the selector is determined.

60 Similar characters of reference designate the same parts wherever they are shown.

The system shown is arranged on the central-battery plan both for signaling and talking. Each line has, as usual, two main conductors or line-wires 1 2, and the central battery *b* is connected in a bridge of the circuit, the negative pole of said battery, with which conductor 1 is connected, being grounded in accordance with the usual practice. A ringing-relay *a* is connected in the bridge between the grounded pole of the battery and conductor 1, and a selecting-relay *c* is also connected in the bridge between the free pole of the battery and conductor 2. The line-wires 1 and 2 are extended through separable contacts controlled by the selector of that line to multiple incoming call terminal pieces or contacts *g' g²* on all the other selectors, so that each line has a pair of terminals on each selector at which the movable contacts of the selector may make connection therewith. Each selector is provided with a rotating arm *f*, arranged to be advanced by a stepping magnet *e* and to be held in its advanced position by a retaining-magnet *d*, said magnets being connected in a local circuit 5 6 7, which is controlled by the selecting-relay *c*, said relay in turn being controlled by the switching mechanism at the subscriber's station. The selector-arm *f* is provided with two contact brushes or wipers *f' f²*, which are arranged to trail over the pairs of stationary line-terminals *h' h²*, arranged in a circle about its axis. The contact-brush *f'* of the selector-arm is arranged to be connected by a conductor 3 with the line conductor 1, of which it forms an extension, said conductor 3 being conductively divided by a condenser *y* and being normally open at contacts of the ringing-relay *a* and a slow-acting relay *k*. Similarly the contact-brush *f²* of the selector-arm is arranged to be connected with line conductor 2 by an ex-

tension 4 of said conductor, said extension being also normally open at other contacts of the slow-acting relay *k*.

The selector-arm carries an insulating-stud 5 *f*⁶, which when said arm is in its idle position serves to maintain a pair of contact-springs *l*' *l*² under tension in engagement with corresponding contact-anvils to extend the circuit of the line conductors 1 2 to the several pairs 10 of multiple contact-terminals *g*' *g*² for incoming calls on the other selectors.

Normally the line conductors 1 2 are thus extended (conductor 2 through a condenser *m*) to their incoming call terminals *g*' *g*²; but 15 when the selector-arm is advanced such normal connections are broken at the springs *l*' *l*², and when relays *a* and *k* are excited the line conductors are connected by extensions 3 and 4 with the selector-arm contact-brushes 20 *f*' *f*², respectively, and by said brushes to the terminals *h*' *h*² of the called line.

Each selector of a party-line is provided with one pair of terminal pieces *h*³ *h*⁴ to represent its own line for "reverting calls"— 25 that is to say, for calls from one subscriber's station to another subscriber's station on the same line. The terminal *h*³ of this pair is connected directly to line conductor 1, while terminal piece *h*⁴ is simply a dummy, having 30 no electrical connection.

Subscriber's station equipment.—As before stated, the advance of the selector-arm at the central office is dependent upon the intermittent closing of the local circuit 5 6 7, which is 35 controlled at a normally open contact of the selecting-relay *c*. To produce an intermittent excitation of this relay *c*, the subscriber's station equipment includes, in addition to the usual telephone apparatus, an interrupter *n*, 40 which when operated will open the metallic circuit and intermittently connect the line conductor 2 to earth by way of a contact *o* of the telephone-hook. The interrupter comprises a toothed wheel *n*', meshing with a 45 pinion, arranged to actuate a contact *n*⁶ as the teeth of the wheel pass in succession under a movable spring. A ratchet-wheel *n*² is mounted to rotate with the toothed wheel *n*', and the controller-arm *n*³, which may be 50 moved forward loosely upon the axis of the wheel against the tension of a coiled spring *n*⁴, carries a pawl *n*⁵, which as the controller-arm is returned by the spring after its advance engages the ratchet-wheel to carry the 55 same and the toothed wheel *n*' around with it, whereby the contact *n*⁶ is made and broken a certain number of times, dependent upon the distance to which the controller-arm has been advanced. The substation equipment also 60 includes a ringing-key *p*, which is adapted to open the metallic circuit and connect the line conductor 2 through normally closed contacts *n*⁷ *n*⁸ of the interrupter mechanism and contact *o* of the switch-hook to earth. While 65 the interrupter is in operation, contacts *n*⁷ *n*⁸

are open, and premature manipulation of the ringing-key will have no effect.

Mechanism for rotating the selector-arm.—

The selector-arm is fastened radially upon a ratchet-wheel *f*³, which is mounted to rotate 70 in a suitable frame. The contact-brush *f*² is in electrical connection with said selector-arm *f* and with the metallic mounting or frame, while the other contact-brush *f*', carried by the selector-arm, is insulated therefrom and connected with a metallic strap *f*⁴, extending along the top of the arm to the axis of rotation thereof, at which point a contact-spring *f*⁵ makes continuous contact therewith. Said contact-spring *f*⁵ is connected to conductor 3. The stepping-magnet *e* is provided with an armature *e*', which carries a pawl *e*², adapted to engage the teeth of the ratchet-wheel *f*³. When the armature is attracted, the pawl advances the ratchet-wheel 85 and the selector-arm is carried thereby one step. The ratchet-wheel is arranged to be held at any point to which it may be advanced by a retaining-pawl *d*², governed by the armature *d*' of the retaining-magnet *d*. 90 When the armature *d*' is in its normal position, it holds the retaining-pawl *d*² out of engagement with the ratchet-wheel; but when said armature is attracted the retaining-pawl is pushed against the ratchet-wheel by a 95 spring. The coöperation of both the stepping-magnet and the retaining-magnet is thus necessary to bring about the rotation of the selector-arm. The retaining-magnet is arranged to act sluggishly in releasing by 100 means of a non-inductive shunt *d*⁴ and by having a small air-gap between its poles and the armature, while the stepping magnet is adapted by contrary arrangements to respond quickly to a cessation of current. 105 These two magnets *d* and *e* are in series in the local circuit 5 6 7, and when a pulsating or intermittent current is passed through the circuit the armature *d*' will be continuously attracted, while armature *e*' is vibrated. The 110 result is a step-by-step advance of the ratchet-wheel and the selector-arm carried thereby, the number of steps of advance being determined by the number of impulses of current applied to the magnets. The sluggish relay 115 *k* is also included in the local circuit 5 6 7, with the stepping and retaining magnets *e* and *d*; but this relay is normally short-circuited by a conductor 8, which is controlled at normally closed contacts of the ringing-relay *a* and also of said relay *k* itself. The 120 ringing-relay being inert during the operation of the interrupter *n* at the subscriber's station, the sluggish relay will not be excited until the selecting operation has been completed. When the sluggish relay *k* is once excited, it holds the short circuit 8 open. A short circuit 9 of the stepping-magnet is arranged to be closed by contacts of the sluggish relay *k* when the same is excited. This 125 130

prevents any further or undesired advance of the selector-arm after the selection has been made, which advance might otherwise be caused when the ringing-key p at the substation is actuated.

Ringing mechanism.—The ringing-generator G of positive pulsating current is included in a grounded conductor 10, which is arranged to be connected at a normally closed contact 10 of ringing-relay a with the conductor 3, which leads through a normally open contact of the sluggish relay k to the contact-brush f' of the selector-arm. The continuity of conductor 10 is normally broken at a contact of 15 the selecting-relay c , which contact is closed when the relay is excited. In order that ringing-current may be applied to the brush f' of the selector-arm and so to the called line, the relays k and c must therefore be excited 20 and the relay a must be inert. Such a condition is brought about when after the selecting operation at the end of which the sluggish relay k has been excited the ringing-key p is actuated at the substation, said key serving to complete the circuit of the selecting-relay c to earth while holding the circuit of the ringing-relay a open.

Busy-test and lock-out mechanism.—The system is provided with means for automatically notifying a calling subscriber when the line called for is already engaged and for preventing interference with an engaged line. A test-relay t has its magnet provided with an initial exciting-winding t' and a locking-winding t^2 . The relay t is adapted when excited to connect line conductor 2 to a conductor 12, leading to the free pole of a grounded battery through the secondary winding u^2 of a "busy-tone" induction-coil u and also to break the local selector-circuit 5 6 7 to de-energize magnets d and e and permit the selector-arm to return to normal position. The relay t , when excited, also closes a locking-circuit 5 14, including the magnet-winding t^2 , 40 said locking-circuit being controlled at contacts of selecting-relay c , which are closed when said selecting-relay is excited. The source of busy-tone current u is also arranged to be connected by a conductor 13 with the several contacts g^2 of the incoming call terminals by way of an alternate contact of the switch-spring l^2 of the selector. The busy-test contact of spring l^2 is closed when the selector-arm is off its normal position, so that 45 at all such times the incoming call terminals g^2 of the line are in connection with the free pole of the battery b' through the secondary winding of the induction-coil which produces the busy tone.

60 Operation of the System.

To make connection with another line, the subscriber begins by taking his telephone-receiver from its hook, whereby the metallic circuit is completed through his telephone

apparatus, and the two polarized relays a and c at the central office both attract their armatures, the relay c closing the local circuit 5 6 7, and so causing the magnets d and e to advance the selector-arm one step. This movement effects no change in the talking-circuits, being merely incidental. The subscriber now turns to his interrupter n , inserts a peg in the hole representing the desired line and rotates the controller-arm n^3 until it is stopped 70 by the peg. This movement separates the contact-springs to break the metallic circuit and connect the normally open interrupter-contact n^6 to the line conductor 2. When the controller-arm n^3 is released, it begins to 80 return under the influence of a spring, the return movement being retarded by an escapement. The interrupter-wheel n' is thus caused alternately to close and open the interrupter-springs, whereby an intermittent 85 current is caused to flow from the central battery b through the selecting-relay c over the line conductor 2 to earth by way of contact o of the subscriber's switch-hook. The armature of the selecting-relay c is thus 90 caused to vibrate in unison with the pulsations of current controlled by the interrupter and so causes corresponding intermittent impulses to be transmitted over the local circuit 5 6 7, governing the selector. The stepping 95 magnet e is thus caused to intermittently attract its armature and so to advance the selector-arm step by step. The selector-arm is held in its advanced position by the retaining-pawl d^2 , controlled by the retaining-magnet, 100 which being made sluggish does not follow the pulsations of the current, but keeps its armature steadily attracted. Just before the controller-arm of the substation device reaches its normal resting position its rotary-movement 105 contact-springs are restored to normal condition, which results in a restoration of the metallic circuit through the telephone apparatus and an interruption of the lead to ground. The restoration of the metallic circuit 110 brings about the energization of the ringing-relay a , which was inert during the selective operation and whose armature in its backward position closed the short circuit 8 around the sluggish relay k . When the 115 ringing-relay a is excited, the short circuit is removed from the slow-acting relay k , which, if the called line is not engaged, attracts its armatures with the following results, first, the stepping magnet e is short-circuited by 120 conductor 9, thus preventing further advance of the selector-arm; second, the talking-circuit is extended by conductors 3 and 4 to the selector contact-brushes f' f^2 , respectively, and so to the called line, and, third, another 125 break is introduced in the short circuit 8 of the sluggish relay at a back contact of said relay, so that when during the ringing operation, presently to be described, the ringing-relay releases its armatures the sluggish re- 130

lay will not be again short-circuited. The subscriber now presses his ringing-key *p*, which grounds the line conductor 2, and then opens the metallic circuit. The selecting-relay *c* is thus maintained excited while the ringing-relay is deenergized. The source of ringing-current *G*, which is positive pulsating current, is thus connected by conductors 10 and 3 to the selector contact-brush *f'*. Current then passes to contact *h'* of the called-subscriber's line out to the called station through the bridge containing the signal-bell and back to ground, partly through the selecting-relay of the called-subscriber's line, but mainly through the non-inductive resistance *c'*, bridged upon that relay through one of its back contacts. When the called subscriber answers, there is established a compound talking-circuit comprising bridged impedances *a a* and *c c* and interconnecting condensers *m y*.

Calling an engaged line.—The subscriber proceeds as before, and the selector-springs arrive at the terminals of the desired but engaged line. The test side *h²* of the line-terminals *h' h²* of an engaged calling-line is put in connection with the free pole of the central battery *b'* by the conductor 13 of such line, while the corresponding terminal *h'* of the engaged line is dead, being separated from battery at the contacts *l'* of such line. The quick-acting test-relay magnet during the selecting operation has its winding *t'* connected in a path 4 11 to ground from the testing contact-brush *f²* of the selector, said path being normally open at a front contact of the ringing-relay. When the selector-arm has arrived at the terminal of the desired line, and the metallic circuit is restored at the rotary-movement springs of the subscriber's interrupter, the ringing-relay *a* attracts its armatures much more quickly than does the sluggish relay *k*, so that for an instant the testing-circuit 4 11 is established to earth from the terminal *h²* of the desired line. If there is a potential on this terminal, as where the line is busy, the test-relay *t* will be excited also before the sluggish relay can respond. When the test-relay is thus excited and draws up its armatures, the conductor 12 is closed to apply busy-tone current to the conductor 2 of the calling-line. A locking-circuit 14 5 is completed through the other winding of the test-relay to maintain the same excited, and the local circuit 5 6 7, containing the selector-magnets *d* and *e*, is broken, so that the selector-arm is released and returns to "zero." The busy-tone current from the grounded secondary winding *u²* flows through the conductor 12, condenser *m*, and line-wire 2 to the substation, passing through the bridged telephone apparatus and back over conductor 1 to the grounded pole of the battery *b*. When the calling subscriber hangs up his telephone-receiver, the local locking-circuit 5 14 is

broken at the front contact of the selecting-relay *c*, and the apparatus returns to normal condition. If the line called for had been free, there would have been no potential on the multiple terminals *h²*, and the test-relay 70 would not have been excited at the end of the selection, but the sluggish relay *k* would have been actuated to complete the talking-circuit, the conductor 11, containing the test-relay, being cut off at the same time. The 75 contact-brushes of the selector-arm make wiping contact with the terminals of all lines as said arm advances to the limit of its movement and retires therefrom; but during such movement the said selector-brushes are 80 "dead" or cut off from all circuit connection until the desired line is reached. The test-relay, furthermore, is kept out of operative relation to the selector until the desired terminal is reached to prevent false tests and 85 lock-outs. Summarizing the testing operation, first, at the moment of test the quick-acting ringing-relay *a* closes the testing-circuit 4 11 through the test-relay *t*, and the latter, also being quick-acting, promptly 90 draws up its armatures, all before the sluggish relay *k* has time to act. The test-relay in responding deprives the sluggish relay of current, and a locking-winding on the test-relay keeps the circuits unchanged until the 95 calling subscriber hangs up his telephone. When a call is transmitted from any line, the incoming call terminals of that line are connected with the source of test-potential through the spring *l²* of the selector, and 100 when connection is made to a line from some other line test-potential from the central battery is applied to the several multiple terminals of the line to which connection is made by way of the selecting-relay *c*, conductor 4, 105 and brush-contact *h²* of the calling-line.

Reverting-calls.—A subscriber on a party-line can signal and converse with any other subscriber on the same line. The operation of selection and ringing is exactly the same 110 as though a subscriber on another line were being called. The selector contact-brushes are caused to advance to terminals *h³ h⁴*, representing the calling-line, of which only the terminal *h³* is used electrically. The ringing-selector contact-brush *f'* is brought into contact with said revertive line-terminal *h³*, and although connection of the selector with line-conductor 1 is broken at the back contact of spring *l'* it remains established at the revertive contact *h³*. When the ringing-key is pressed after the selecting operation, the ringing-relay armature falls back and closes the ringing-circuit 10 3 to the ringing-selector spring *f'*, thence to the revertive line-terminal and conductor 1, from which two paths to earth are provided—one through the bells and condensers bridged across the line at stations other than that of the calling subscriber to conductor 2 and thence to earth at 125 130

the ringing-key of the calling subscriber, the other through the ringing-relay *a* to the grounded pole of the battery. The relays *a* and *c* are both polarized, and relay *a* is biased 5 in such a way as not to respond to the positive pulsating ringing-current. In calling another substation on the same line or one of the substations on another party-line the calling subscriber rings in accordance with 10 the code-number signal of the station wanted. While two subscribers on the same line are engaged in conversation, their line is busy to other subscribers who may call, because of the advance of the selector-arm from its normal position and the consequent connection 15 of the multiple terminals g^1 g^2 to conductor 13 and the busy-tone transformer.

Miscellaneous features.—A subscriber under all circumstances is free to operate his selector—that is, if line A calls line B, line B can disconnect from line A and make any desired selection. When line B does this, the springs l^1 l^2 of line B's selector are operated, and the busy tone is applied by conductor 13 20 to the calling-line to notify the calling subscriber of the change. It will be observed that conductor 13 of the called line, including the secondary u^2 of the busy-tone transformer, forms a shunt around the selecting- 25 relay *c* of the calling-line, so that the said secondary winding should have sufficient resistance to prevent the selecting-relay from releasing its armatures. The interposition of condensers between the line-circuits in addition to other functions permits either subscriber to disconnect or reselect at will. The non-inductive shunt around the selecting-relay *c* is placed there to keep the relay from being chattered when a line is being signaled, 30 the shunt being of such resistance that it carries most of the ringing-current from the relay, yet without interfering with its operation by direct current. I will be noted that when the telephone is on the hook at the substation the ground is cut off at contact *o*, so 35 that purposeless manipulation of the interrupter-arm or the ringing-key will have no effect on the central-station apparatus. So, also, during the selecting operation before the 40 interrupter-arm has returned to normal position the path to ground controlled by the ringing-key is opened by the rotary-movement springs of the interrupter, so that the actuation of the ringing-key before the selecting operation is completed will have no effect. It will be noted that the "ringing- 45 lead" from the generator at a back contact of the ringing-relay *a* is normally open at contacts of the selecting-relay *c*. This provision is to prevent an undesired short ring 50 of the bells on a called line, which would otherwise occur just as the calling subscriber hangs up. The ringing-relay of the calling subscriber releases its armature more 55 quickly than the retaining-magnet can re-

lease the selector-arm, and the contact-brush *f'* of the selector would be momentarily connected, through the source of ringing-current, to the back contact of the calling-subscriber's ringing-relay if the ringing-lead were not 60 opened at the same instant by the selecting-relay.

It will be observed that the apparatus of the substation is the same as that of Patent No. 772,023 of October 11, 1904, except that 75 the contact *o* of the switch-hook has been added to prevent disturbance of the central-station apparatus during purposeless manipulation of the substation parts while the receiver is resting on the hook. Also I will 80 mention the fact that there are other forms of selecting apparatus embodying trailing contacts, quick-acting stepping magnets, and slow-acting retaining-magnets that are adapted to be used in my system. I therefore do 85 not confine my claims to the specific details of construction illustrated.

I claim—

1. In an automatic telephone-exchange, the combination with a telephone-line, of a selector individual to the line having a movable contact-brush, stationary contact-terminals of other lines, and electromagnetic stepping mechanism for trailing said contact-brush across said terminals, a selecting-interrupter at the substation arranged to control said electromagnetic mechanism to advance the contact-brush to the terminals of a wanted line, a relay *k* in a local circuit with said stepping mechanism adapted to connect 90 the said contact-brush with the calling-line, a short circuit for said relay, and a switch at the substation actuated in the return of the selecting-interrupter to its normal position or maintaining said short circuit during the operation of said interrupter, whereby the telephone-line is disconnected from the contact-brush of its selector during the selecting operation and then connected with said brush, 95 substantially as set forth.

2. In an automatic telephone-exchange, the combination with a selector having a movable contact-brush adapted to form the terminal of a calling-line, stationary contacts of other lines with which said movable brush is 100 adapted to be engaged, means for applying test-potential to the stationary contact-terminal of a busy line, a local test-circuit from said movable contact-brush, including the winding of a test-relay, busy-notification apparatus controlled by said test-relay, a selecting-interrupter at the substation, a switch actuated upon the return of said interrupter to its normal position after the selecting operation, means at the central office controlled 105 by said switch for closing the test-circuit, a slow-acting relay *k* at the central office controlling said test-circuit, said relay *k* being also controlled through the agency of said substation-switch, said relay *k* being adapted 110 115 120 125 130

- when excited to extend the circuit of the calling-line to said movable contact-brush, and means controlled in response to the test-relay for blocking said slow-acting relay, where-
5 by the movable contact-brush remains dis-
connected from the calling-line when the
called line is busy, but when the called line is
not busy the test-relay is cut off in the re-
sponse of said relay *k*.
- 10 3. In an automatic telephone-exchange, the combination with a telephone-line, of the selecting and ringing relays *a* and *c*, and means at the substation for controlling said relays independently and simultaneously, of the selector comprising a switch, a stepping magnet and a retaining-magnet, a slow-acting connecting-relay and a test-relay ar-
ranged to cut out each other when excited, a local circuit including said stepping and re-
taining magnets and said connecting-relay,
controlled by said selecting-relay, a circuit
for the test-relay closed by said ringing-relay
and a short circuit 8 of the connecting-relay
opened by said ringing-relay, when the same
is excited, said connecting-relay having con-
tacts adapted when the relay is excited to
open said short circuit 8 at another point
and to close a short circuit of the stepping
magnet, whereby upon the response of said
connecting-relay it is maintained excited
and the selector-switch maintained station-
ary under the control of the selecting-relay
alone. 75
- 15 4. In an automatic telephone-exchange, the combination with the selector-switch, the stepping and retaining magnets therefor, a local circuit including said magnets, and means for controlling said circuit from the substation, of a connecting-relay *k* adapted to com-
plete the circuit of the line to the selector-
switch, a selecting-relay *c*, a ringing-relay *a*,
means for controlling said relays *a* and *c* in-
dependently or simultaneously from the sub-
station, a local circuit including the stepping
magnet, the retaining-magnet and the con-
necting-relay *k*, controlled by the selecting-
relay *c*, and a short circuit of the connecting-
relay controlled by the ringing-relay *a*. 80
- 20 5. In an automatic telephone-exchange, the combination with the selector-switch, the stepping and retaining magnets therefor, a local circuit including said magnets, and means for controlling said circuit from the substation, of a connecting-relay *k* adapted to com-
plete connection of the line through to the selector-switch, means for exciting said relay controlled at the substation in the selecting-transmitter mechanism, and a short circuit of the stepping magnet established in
35 the response of said connecting-relay. 85
- 25 6. In an automatic telephone-exchange, the combination with a telephone-line, of a selector comprising a switch-arm, stepping and retaining magnets and a slow-acting connecting-relay *k* adapted to extend the circuit of the line to the selector-switch, a selecting-relay controlling a local circuit through the stepping and retaining magnets and through the magnet of connecting-relay
40 *k*, a test-relay *t*, said relays *k* and *t* being each adapted when excited to cut out the other, a ringing-relay *a*, a test-circuit bringing the test-relay into operative relation to the selector to respond to a test-potential at the
45 terminal of the wanted line, said test-circuit being closed by the ringing-relay *a* when excited, said relay *a* being also adapted when excited to break a short circuit normally maintained thereby around the connecting-
50 relay, and selecting-transmitter mechanism at the substation adapted first to intermittently close the circuit of the selecting-relay and finally to close the circuit of both selecting and ringing relays, whereby the selector-
55 arm is advanced by the stepping magnet of the terminal of the wanted line, the circuit of the test-relay is made momentarily effective, and the connection is finally completed upon the response of the relay *k* if the wanted line
60 is free, or blocked if the test-relay is excited. 100
6. In an automatic telephone-exchange, the combination with a telephone-line, of the selecting and ringing relays *a* and *c*, and means at the substation for controlling said relays independently and simultaneously, of the selector comprising a switch, a stepping magnet and a retaining-magnet, a slow-acting connecting-relay and a test-relay ar-
ranged to cut out each other when excited, a local circuit including said stepping and re-
taining magnets and said connecting-relay,
controlled by said selecting-relay, a circuit
for the test-relay closed by said ringing-relay
and a short circuit 8 of the connecting-relay
opened by said ringing-relay, when the same
is excited, said connecting-relay having con-
tacts adapted when the relay is excited to
open said short circuit 8 at another point
and to close a short circuit of the stepping
magnet, whereby upon the response of said
connecting-relay it is maintained excited
and the selector-switch maintained station-
ary under the control of the selecting-relay
alone. 105
7. In an automatic telephone-exchange, the combination with a telephone-line, of a selector comprising connection-terminals for the other telephone-lines and a movable switch-arm carrying brushes adapted to trail over said terminals in the movement of the arm, a stepping magnet adapted when energized to advance said arm, a retaining-magnet adapted to hold said arm in its advanced position, a connecting-magnet controlling the connection of said brushes with the line, a circuit for said magnets, a normally closed shunt about said connecting-magnet, switching mechanism at the substation adapted to effect the intermittent completion of said circuit to cause the stepping magnet to advance the arm to the desired terminals, and means controlled from the substation adapted to open said short circuit after said switch-arm reaches the proper terminal. 110
8. In an automatic telephone-exchange, the combination with a telephone-line extending in two limbs 1, 2, from a substation to the poles of a grounded source of current, of a switch at the substation controlling the circuit, a relay *c* at the central office between the free pole of said battery and the line, a selector carrying connection-terminals for each of the other telephone-lines, a movable switch-arm for said selector carrying brushes adapted to trail over said terminals in the movement of the switch-arm, electromagnetic mechanism for advancing said arm, a circuit for said mechanism controlled by relay *c*, selective mechanism at the substation adapted to open the line-circuit and intermittently ground the limb of the line connected with the free pole of the battery; whereby the switch-arm may be advanced into engagement with the terminals of any desired line, normally open branches leading 130

from said limbs 1, 2, to the brushes of said arm, a relay controlling the continuity of said branches, a circuit for said relay, a relay *a* controlled from the substation adapted to complete said circuit as said brushes reach the desired connection-terminals, a source of ringing-current, and means controlled at the substation for connecting the same with said branches after the brushes reach the proper terminals.

9. In an automatic telephone-exchange, the combination with a telephone-line extending in two limbs 1, 2, from a substation to the poles of a grounded central battery, a relay *c* between the free pole of said battery and one limb of the line, a selector carrying connection-terminals for the other telephone-lines and a movable switch-arm having brushes adapted to engage said terminals in the movement of said arm, normally open branches leading from said limbs 1, 2, to said brushes, a magnet for advancing said arm, a retaining-magnet adapted to hold the arm in its advanced position, a magnet *k* controlling the continuity of said branches, a circuit including all of said magnets controlled by relay *c*, a normally closed shunt around magnet *k*, selective step-by-step mechanism at the substation adapted to first open the line-circuit and successively ground the limb of the line connected with the free pole of the battery, whereby relay *c* makes and breaks the circuit of the stepping magnet to advance the switch-arm to the desired connection-terminal, a relay *a* controlled from the substation adapted, as the switch-arm reaches the end of its travel, to break the shunt around relay *k*, and a shunt around the stepping magnet closed by relay *k* when energized.

10. In an automatic telephone-exchange, the combination with a telephone-line, a selector at the central office comprising connection-terminals for the other lines in the exchange and a movable switch-arm carrying brushes adapted to engage said terminals, electromagnetic mechanism controlled from the substation adapted to advance said switch-arm; whereby said brushes may be brought into engagement with the terminals of any desired line, a sluggish-acting relay *k* controlling the connection of said brushes with the line, a circuit for said relay, a switch at the substation adapted to complete said circuit after the switch-arm reaches the proper terminal, a test-relay connected during the test of the called line from earth through contacts controlled by relay *k* with the switch-arm, a grounded source of current associated with each of the other lines, means for connecting the free pole of said battery with the free connection-terminals of any busy line

upon the different selectors, a source of tone-producing current adapted to be connected with the calling-line by said test-relay, and normally closed contacts included in the circuit of said sluggish relay controlled by said test-relay; whereby if the line wanted is busy the circuit of the test-relay will be completed to apply the busy-test current to the line and open the circuit of relay *k*, but if the called line is free, the relay *k* in connecting the switch-arm with the calling-line will disconnect the test-relay from the switch-arm.

11. In an automatic telephone-exchange, the combination with a telephone-line, of a selector for said line comprising connection-terminals for the other lines and a movable switch-arm carrying brushes adapted to engage said terminals, a similar individual selector for each of the other lines, a stepping magnet adapted to advance said switch-arm, a retaining-magnet adapted to hold the switch-arm in its advanced position, a circuit for said magnets, mechanism controlled from the substation adapted to successively make and break said circuit to effect the advancement of said switch-arm, a sluggish-acting relay *k* controlling the connection of said brushes with the line, a circuit for said magnet, a switch at the substation adapted to complete said circuit after the brushes reach the proper terminals, a quick-acting test-relay connected the instant the brushes make connection with the called line from earth through contacts of relay *k* with one of the brushes of the switch-arm, a source of grounded current connected with all the corresponding free terminals of a busy line, a source of tone-test current adapted to be connected with the calling-line by said relay when energized, normally closed contacts included in the circuit of said sluggish relay and controlled by the test-relay, a source of ringing-current, a relay *a* controlled from the substation adapted to connect said source with one of the brushes when relay *k* becomes energized, a locking-winding for the test-relay, and a circuit for said winding controlled jointly by said relay *c* and the test-relay; whereby if the wanted line is busy the test-relay is operated to open the circuit of relay *k* and apply busy-test current to the calling-line, but if the called line is free, relay *k* is energized, connecting the brushes with the calling-line, disconnecting the test-relay from the switch-arm, and permitting relay *a* to apply ringing-current to said brush.

In witness whereof I hereunto subscribe my name this 19th day of July, A. D. 1905.

ALBERT M. BULLARD.
